UNITED STATES PATENT OFFICE

2,482,259

HAIRPIN

Robert N. Gernheuser, Toledo, Ohio, assignor to
Gernheuser Industries, Inc., Toledo, Ohio, a
corporation of Ohio

Application January 27, 1947, Serial No. 724,626

1 Claim. (Cl. 132—50)

1

This invention relates to hairpins of the bobby type and an object of this invention is to produce a pin of the type described having readily formed and simple hair gripping means for preventing inadvertent relative movement of the pin from the hair gripping position.

Another object is to produce a bobby pin having a pair of hair gripping arms joined by means of a novel construction which not only increases the useful life of the pin but enhances the resiliency and gripping action of the arms.

A further object is to produce a bobby pin having a pair of resilient arms formed with multiple angularly arranged hair gripping channels by means of which the pin is retained in the hair gripping position.

These and other objects and advantages will become apparent from the following description and claim and for purposes of illustration but not of limitation, embodiments of the invention are shown in the accompanying drawings, in which

Figure 1 is a side elevational view of a bobby pin embodying the features of this invention;

Figure 2 is a view from the bottom side of the pin illustration in Figure 1;

Figure 3 is an elevational view of the loop end of the pin illustrated in Figure 1;

Figure 4 is an elevational view of the open end of the pin illustrated in Figure 1;

Figure 5 is a top plan view of another form of bobby pin; and

Figure 6 is an enlarged fragmentary sectional view taken along the line 6—6 of Figure 5.

In the drawings, Figures 1 to 4 inclusive illustrate a bobby pin formed of a narrow band 10 of resilient material, such, for example, as metal, plastics, hard rubber and the like. An intermediate portion of the narrow band 10 is looped, as at 11, through the greater part of two complete turns so that the remaining end portions of the band extend in one direction as a pair of legs 12 and 13 which are constantly urged in the direction to contact each other along their inner faces.

One leg 12 is longer than the other and outwardly bowed. The surfaces of this leg are substantially unmodified. The other leg 13 is provided with a plurality of V-shaped, arcuate or other similarly shaped crimps 14 arranged in a longitudinal row along the arm in angular relation with both the longitudinal and transverse axes. Alternate crimps may be formed in parallel relation with each other but in angular relation with adjacent crimps. Although they may

be formed at angles ranging from 0 to 60 degrees with the transverse axis, they preferably are at angles of 45 degrees so that the adjacent hair receiving channels 15 extend substantially in perpendicular relation to each other. The end portion of the leg 13 is turned outwardly in the form of a lip 16 which diverges from the first leg 12. It is apparent that the looping connection 11 provides greater flexibility to the arms 12 and 13. Yet, in operation, less flexing actually takes place per unit length of material in the connection, so that fatigue and permanent deformation are substantially reduced. As a result, the spring forces urging the legs together are more uniform throughout the life of the pin, which, by means of this arrangement is materially extended.

When in the hair gripping position, the bundles of hair, which are disposed in the longitudinally spaced channels 15, operate effectively to militate against relative longitudinal movement of the pin until the legs are forced apart. This is because the hair bundles do not readily pass from one channel to the next in view of the restricted space between the substantially contacting inner faces of the legs in the area between the channels. By means of these same channels, adjacent hair bundles are angularly disposed with relation to each other, each hair bundle converging towards one and diverging from the other of the adjacent hair bundles and, as a result, the pin is effectively held against relative transverse movement. As an illustration, when the pin is shifted, while in its gripping position, in the direction towards the roots of the hairs engaged therein, the hairs disposed in channel a are drawn apart from the hairs in channel b and the hairs in channel c are drawn towards the hairs in channel b. Since the hair roots are stationarily anchored to the scalp, it is evident that the forces moving the pin must overcome the effort required for the readjustment of some of the hairs from one channel to the next adjacent channel.

Another modification of pin embodying the salient features of this invention is shown in Figures 5 and 6. In the main, the pin is substantially the same as that described, the differences residing in the construction and arrangement of the shorter leg 13a. In this modification, multiple serrations 20 or grooves are provided on the inner face along the length of the leg 13a which, being substantially straight, is adapted to abut the other leg 12a throughout the greater portion of its length. A lip 16a is formed on the end of the straight portion to aid in separating

the legs in use. These serrations are arranged angularly with respect to the transverse and longitudinal axes of the leg. A group, such for example, as three serrations, may be arranged adjacent each other in parallel relation but in angular relation with the next adjacent groups, or else, the adjacent serrations may each be in angular relation with each other. In either case, there is provided on the inner face of the arm 13a multiple angularly arranged grooves which operate in combination with the hairs disposed between the legs to hold the pin and hairs against relative movement in any direction.

It is manifest that I have produced a new and novel hairpin having many novel features of construction and arrangement which not only enhance the useful life of the pin but its effectiveness in position of use. The angular relationship of the hair-receiving channels enables the pin to be used in any position on the head without loss of effectiveness, and the simplicity by which the improved construction and arrangement are obtained enables the pin to be readily manufactured on a mass production basis.

It is to be understood that numerous changes in details of construction and arrangement of the elements can be made without departing from the spirit of the invention especially as defined in the appended claim.

What I claim is:

A bobby pin comprising a strip of substantially flat spring metal bent up itself to provide a pair of hair gripping arms normally urged toward each other, a plurality of straight grooves in the inner face of one of said arms, said grooves extending generally diagonally across said arm from edge to edge of said arm, some of said grooves extending in one direction and others in a different direction whereby said grooves converge toward an edge of the said one arm and others converge toward the opposite edge of said one arm so as to deter broadside slippage of said pin with respect to the hair gripped thereby.
